CUT-OFF MECHANISM FOR STRAW MAKING MACHINES

Karl E. Garling, Newark, N. J., assignor, by mesne assignments, to Berst-Forster-Dixfield Co., New York, N. Y., a corporation of Maine

Application July 21, 1932, Serial No. 623,761

9 Claims. (Cl. 164—42)

Among the principal objects which the present invention has in view are: to sever paper tubes made in imitation of straws without interrupting the feed of the tube; to simplify the operation 5 mechanism; and to facilitate the replacement of the cutting element.

In the drawings:

Figure 1 is a face view of the cut-off mechanism.

10 Figure 2 is a side edge view of the same.

Figure 3 is a detailed view on enlarged scale and in horizontal section showing a fragment of the tube referred to, the guide therefor, and the cutting arm and blade, the section being 15 taken as on the line 3—3 in Figure 1, and the blade being disposed in its first position prior to contact with the straw.

Figure 4 is a similar view showing the blade as having penetrated the straw.

20 Figure 5 is a diagrammatic view showing the three positions of the cutting blade and supporting arm therefor, these positions being indicated by the numerals 1 to 3, respectively.

Figure 6 is a diagrammatic view showing the 25 position assumed by the blade and supporting arm as the blade is being returned to its initial position.

Figure 7 is a similar view showing the blade and the supporting arm in its position to pass 30 under the straw.

Figure 8 is a perspective view of a certain cam shaped member for engagement by the blade for positively flexing the same.

The present mechanism is particularly designed 35 to cut in desired lengths the spirally wound paper straw indicated in the drawings by the letter X.

These straws are manufactured by suitable mechanism and delivered through a guide tube 40 12. The tube 12 is fixedly mounted in a standard 13, the termination tube being in line with the guide block 14 which is likewise mounted on the standard 13. Against the block 14 there generally rests the cutting blade 15 when inactively disposed.

The blade 15 is constructed from very thin metal and of suitable length to increase the flexibility of the blade to offer as little resistance 50 as possible to the straws X as the same are continuously fed forward and particularly during the operation of the blade.

The dominant purpose of the mechanism is to sever the straws X by means of the flexible blade 55 15 without mashing or otherwise injuring the

severed end of the straw. This is contributed to by the action of the spiral spring 16.

The spring 16 is suitably anchored on some stationary element of the machine that the present mechanism is mounted upon. The free end 5 of the spring is attached to the swinging arm 17 upon which the blade 15 is mounted. The blade 15 is held in position on the arm 17 by means of the clamp plate 18 and the bolts 19. A pin 20 is extended from the plate 18 for 10 to the blade 15 to rest upon and to hold it in its service position. The swinging arm 17 is pivotally mounted upon the crank 21 set out from the gear wheel 22. In its normal position the swinging arm rests upon the block 23 on the 15 standard 13.

To adjust the block 23, a couple of bolts 24 are provided in the operation of which the block 23 can be moved forward or allowed to retract. In this position shown by dotted lines in Figure 20 5 of the drawings, the spring 16 is in its most relaxed position. From this position it is moved by means of a semi-cylindrical stub 25 which is mounted on the gear wheel 26.

The wheels 22 and 26 are meshed to move in 25 unison and harmony. The wheel 22 is mounted on a shaft 21 which is operatively connected with a power mechanism as will be seen by reference to Figures 6 and 7 of the drawings. The stub 25 engages an offset block 28 on the swing- 30 ing arm 17. As the wheel 26 rotates, the stub 25 is carried off from the position shown in Figure 7 to the position shown in broken lines in Figure 5, where the flat side of the stub is on the eve of passing the inclined surface at the bottom 35 of the block 28.

While the arm 17 is being thus swung about its crank 21, the said crank is moving from the position shown in broken and dotted lines in Figure 5 to the position shown in full lines in 40 Figures 5, 6 and 7, with the result that the arm 17 and blade 15 carried thereby are lowered so that the blade 15 is moved by the stub 25 under the straw X to the position shown by broken lines in Figure 5, and while the arm 17 is being 45 thus moved by the stub 25 it is simultaneously moved by the crank 21 from the position shown in Figure 7 to that shown by broken lines in Figure 5.

It will be noted that in the position shown by 50 broken lines in Figure 5, the blade 15 has been elevated until the extremity thereof is horizontally in line with the straw X. It will also be noted that at this moment the stub 25 is passing out of engagement with the latch block 28 55

so that the instant the said latch block is released, the spring 16 is permitted to move the arm 17 to the position shown by dotted lines in Figure 5 or that where the arm 17 rests on the block 23.

In thus passing, the flexible blade 15 passes through the straw X to sever the same without interrupting the progress of the straw, since the blade is flexed by the pressure of the straw thereagainst. It is also to be noted that the blade has a motion partially in a longitudinal direction with respect to the blade so as to obtain a slicing action upon the straw as distinguished from a direct chopping action. The cutting edge of the blade accordingly has a relative longitudinal movement with respect to the straw and as the straw is rotating with the side thereof toward the blade moving in the same direction as the slicing movement of the blade the cutting is more readily accomplished and more positively overcomes the tendency to pinch the tube upon first engagement of the blade with the tube. It may also be added that since the blade has a longitudinal movement with respect to the straw, the engagement of the straw against the blade progressively advances toward the free end of the blade with the simultaneous advancement of the straw toward the blade, as a consequence of which as greater flexing in the blade is necessary to accommodate the further protrusion of the straw, engagement of the straw with the blade moves outwardly of the blade where greater flexing is permitted.

In Figure 4 of the drawings is indicated the effect which the straw X has upon the blade 15 slightly bending or deflecting the same, a movement permitted by the high flexibility of the blade 15. It is to be noted that blade 15 prior to being passed through the straw rests flatwise against block 14 so that any vibration which has previously been set up in the blade due to flexing, is damped and stopped by the flatwise engagement against the said block.

In certain cases and to insure the flexing of the blade 15, I provide, as shown in Figure 8, a cam-shaped member 29 against the surface of which the blade 15 rests as it is drawn by the spring 16 through the straw. The face of the cam is pitched to accord with the advance of the straw X, when being delivered by the machine through the guide tube 12.

I claim:

1. A mechanism as characterized having a cutting member for severing a moving straw, said member comprising an elongated flat thin metal blade adapted to yield to the pressure of the straw in the direction of movement of said straw when passing through said straw, and means for moving said blade through said straw, said means embodying a spring-actuated latch-restrained member, and means for returning said blade to its restrained position, said means embodying a flattened member protruding into the path of said latch-restrained member, said flattened member being mounted upon and to move with a power-driven wheel.

2. A mechanism as characterized having a cutting member for severing a moving straw, said member being adapted to yield in the direction of movement of said straw while passing through said straw, means for moving said blade through said straw, said means embodying a spring-actuated latch-restrained member, and means for returning said blade to its restrained position, said means embodying a pressure member to engage said latch-restrained member to move same to its

original position against the tension of the spring for actuating said member until released by said pressure member, and means for reciprocating vertically said latch-restrained member and blade carried thereby to lower said blade out of the path of said straw while being returned to its original position and to lift the same to its original position prior to the release of said latch-restrained member by said pressure member.

3. A mechanism as characterized having a cutting member for severing a moving straw, said member being adapted to yield in the direction of the travel of said straw while passing through said straw, and means for operating said blade comprising a latch arm for holding said blade, a spring adapted to draw said blade through said straw, a gear wheel having a crank-like pivotal connection with said latch arm to elevate and lower the same to place said blade into and out of cutting relation to said straw, and a gear wheel to operatively engage the previously mentioned gear wheel and having an extension therefrom adapted to engage and disengage said latch arm to move the same to its initial position where the cutting blade is disposed to cut the straw when the latch arm is released.

4. In a tube forming machine, the combination with means for continuously feeding a formed tube, of a cutter blade for severing the said tube, means for pivotally mounting the said blade, means for effecting two-dimensional orbital movement of the pivot of said mounting means, and means for effecting a different two-dimensional orbital movement of the cutter blade.

5. A tube-forming machine comprising means for continuously feeding a formed tube, a flexible cutter blade mounted to traverse the path of said tube, and means for flexing said blade during the entire period of the blade crossing the path of the tube at a rate corresponding to the rate of feeding of the straw.

6. A tube-forming machine comprising means for continuously feeding a formed tube, a flexible cutter blade mounted to traverse the path of said tube, and a cam face engaged by said blade causing said blade to flex at a rate corresponding to the rate of feeding of the tube while traversing the path of the tube.

7. In a cut-off mechanism for severing a continuously forwardly fed substantially rigid tube, a cutter having a normal path across the path of the tube perpendicular to the axis of the tube and said cutter having a greater length than width and providing a longitudinal cutting edge which traverses the path of the tube with a slicing motion with respect to the tube, said cutter being thin and readily flexed transverse to its length, whereby the portion of the cutter in contact with the tube while cutting the same will be carried forward with the tube by flexing the blade.

8. In a cut-off mechanism for severing a continuously forwardly fed substantially rigid tube, a cutter having an orbital path of movement across the path of the tube perpendicular to the axis of the tube, said cutter traversing at high speed in one portion of its orbital path the path of movement of the tube with a slicing motion by which the cutting edge of said cutter has a longitudinal movement as it crosses the path of movement of the tube and flexes entirely across itself under pressure of the advancing action of the tube thereagainst without distorting or buckling the tube.

9. In a tube forming machine, the combination with means for continuously feeding a formed

5 tube, of a cutter blade having a greater length than width, said blade being movable transversely in its own plane perpendicular to the axis of the tube with a component of movement longitudinally of its cutting edge and in the direction of movement of the side of the straw toward said cutting edge, said blade being momentarily flexi-

ble for its entire width longitudinally with respect to the path of movement of the tube, said blade severing the tube and the cut end of the tube engaging the adjacent face of the blade and flexing the blade during simultaneous movement of 5 both the tube and blade.

KARL E. GARLING.
